UNITED STATES PATENT OFFICE.

JAMES E. WILLIAMSON, OF MANSFIELD BOROUGH, PENNSYLVANIA.

MOTOR-PLOW.

1,241,320.

Specification of Letters Patent. Patented Sept. 25, 1917.

Application filed February 24, 1917. Serial No. 150,675.

To all whom it may concern:

Be it known that I, JAMES E. WILLIAMSON, a citizen of the United States, residing at the borough of Mansfield, in the county of

5 Tioga and State of Pennsylvania, have invented certain useful Improvements in Motor-Plows, of which the following is a specification, reference being had therein to the accompanying drawing.

10 This invention relates generally to improvements in plows and more particularly has reference to an improved motor plow.

The present invention has for its particular aim and object to provide a motor plow embodying novel driving means whereby the improved plow carrying main frame may be propelled forwardly and rearwardly over a field without necessitating turning of the frame, thereby facilitating the plowing of 20 the field and saving considerable time and labor that is normally consumed in properly adjusting a plowing machine of the types at present in use.

It is an additional object of this invention to provide novel means for shifting the head or end wheels when the plow reaches the ends of a field that is being plowed, clutch means coöoperating with the head wheels, which serve as auxiliary driving 30 wheels, for disconnecting them from the driving means during the shifting operation.

More particularly, the present invention embraces the construction of the improved frame having the adjustable plowing means 35 on the respective ends thereof, improved lifting means acting in conjunction with the plowing means for properly adjusting the plows during the operation of the machine.

Among the other aims and objects of the 40 present invention may be recited the provision of a machine of the character mentioned with a view to compactness, the construction of which is simple, the cost of production comparatively low and the efficiency 45 high.

Other objects as well as the nature, characteristic features and scope of this invention will be more readily apparent from the following description taken in connection 50 with the accompanying drawings and pointed out in the claims, forming a part of this specification.

The preferred embodiment of the present

invention is clearly illustrated in the accompanying drawings, in which:—

55

Figure 1 is a side elevation of the improved plow.

Fig. 2 is a top plan thereof.

Fig. 3 is an end elevation.

Fig. 4 is a detail of one of the head wheels. 60

Fig. 5 is a detail of the driving means.

Fig. 6 is still another detail.

Similar characters of reference are employed in all of the above described views, to indicate corresponding parts.

65

Referring now, more particularly, to the accompanying drawings I provide a main supporting frame including side bars 1 and 2 the latter being shorter than the former and connected thereto by means of transverse end bars 3. Braces 4 extend diagonally from points intermediate the ends of side bar 2 and are connected adjacent the outer ends of the side bar 1 to increase the rigidity of these portions of the bar 1. Arches 5 carrying upstanding studs 6 on their intermediate portions, the latter being journaled in the outer ends of the bar 1 while axles 7 are journaled in the outer ends of the arches. The head wheels 8 are carried by the axles 7 for supporting one side of the frame. Sprocket wheels 9 are carried on the inner projecting ends of the shaft 7 for a purpose that will presently appear. The opposite side of the frame is supported by the main wheel 10 carried by a shaft 11 the respective ends of which are journaled in a bearing 12 carried by the under surface of the bar 2 at a point substantially intermediate the ends thereof and in an auxiliary side bar 13 90 the respective ends of which are connected adjacent the ends of the side bar 2 as indicated in the drawings.

85

With a view toward connecting the plowing means to the frame I employ two pairs 95 or sets of gang plows 14 and 15, the beams 16 of which are pivotally supported on the end bars 3 while the plow points 17 of the plows 14 and 15 are arranged upon opposite sides of the wheel 10 and extend in 100 opposite directions toward the respective ends of the frame as indicated in the drawings. In order to raise either set of the plows 14 and 15 I have pivotally mounted levers 18 in the frame the forked ends 19 105 of which have links 20 pivotally connected

thereto, the outer ends of the links in turn being pivotally connected to the beams of the plows adjacent the mold boards thereof. These levers may be held in adjusted position with respect to the frame by means of pawls 21 slidably and resiliently mounted on the handle portions of the levers 18 and engageable with any of the teeth of one of the segmental racks 22 mounted on the frame. A hand lever 23 is pivoted to the outer end of each lever 18 and is connected to the pawl by means of a rod 24 for moving the pawl against the tension of the spring 25 which is arranged to normally hold the pawl in engagement with one of the teeth of the rack.

For the purpose of driving the frame forwardly and rearwardly over the ground I have provided an improved platform support 26 the legs 27 of which are connected to the transversely extending cross bars 28 on the frame. An engine 29 of any suitable type is mounted on the supporting platform 26 while a transmission gear casing 30 is mounted on the platform so that the gears thereof, (not shown) are arranged in operable relation with the engine shaft and actuated by a controlling lever 31 for imparting an alternate rotary motion to the shaft 32. A stub shaft 33 is journaled on one side of the supporting platform and carries a bevel gear 34 on the upper end thereof which meshes with the bevel gear 35 on the outer end of the shaft 32. Another bevel gear 36 is mounted on the lower end of the shaft 33 and meshes with a large bevel gear 37 mounted on the inner end of a shaft 38, which in turn is journaled at a point substantially intermediate the ends of the side bar 2 and in the longitudinal bar 38' of the frame. A gear 39 is carried by the outer projecting end of the shaft 38 and meshes with another gear 40 carried by the axle 11 so that upon starting of the engine and the adjusting of the gears in the transmission casing, the wheel 10 will be ultimately driven in a corresponding direction owing to this gearing mechanism. In order to impart a corresponding motion to the head wheels a shaft 41 is journaled transversely of the frame in the side bar 1 and the longitudinal bar 38' thereof and carries a bevel gear 42 on one end which meshes with the bevel gear 36 on the shaft 33. Another gear 43 is carried by the shaft adjacent the opposite end and at all times meshes with a similarly formed gear 44 loosely mounted on another shaft 45, the latter in turn being journaled transversely of the frame and in spaced parallel relation with the shaft 41. A clutch member 46 is carried by one face of the loosely mounted gear 44 while a collar 47 serves to prevent sliding movement of this gear. Another clutch member 48 is

slidably mounted on a key 49 on the shaft 65 and is adapted to be moved into engagement with the clutch member 46 by adjusting means 50. This adjusting means may be said to consist of a pivotally mounted bell crank lever 51 on the frame, the lower forked end of which lever is arranged in a groove in the clutch member 48 as shown at 52 while the lever 51 extends through a slot in the platform so as to position the upper handle portion 54 in proximity to the driver 75 so as to permit of the shifting of the clutch members and thus rotate the shaft 45 when desired. Sprocket wheels 55 and 56 are carried in spaced relation on the shaft 45 while chains 57 and 58 are loosely trained about the respective sprocket wheels and also about the sprocket wheels 9 and as will be readily apparent, when the clutch members are in engagement with each other rotary movement will be transmitted from the shaft 45 to the axles 7 to consequently rotate the wheels in a corresponding direction.

As intimated, means have been provided for shifting the head wheels 8 and in accomplishing this purpose worm wheels 59 are carried by the upper ends of the studs 6 while the worm wheels are arranged in mesh with the worms 60 formed adjacent the inner ends of the steering rods 61 journaled in bearings 62 adjacent the outer ends of 95 the bar 1 and also in bearings 63 mounted on the frame. Steering wheels 64 mounted on the opposite ends of the steering rods are respectively arranged above the driver's or operator's supporting platforms 65 as indicated in the drawings.

The operation of the present invention may be reviewed as follows:

Assuming that the parts have been assembled in the manner described and it is desired to plow a field, the plows 14 are properly adjusted in the ground while the plows 15 are removed from engagement with the ground, this operation being effected by adjusting the hand levers 18. The engine 29 is now started in the usual manner subsequent to adjusting the gears in the transmission by the controlling lever 31. This causes the gear wheel 35 which meshes with the gear 34 to impart rotary motion to the shaft 33 and 115 rotary motion is in turn imparted to the shaft 38 through the medium of the gears 36 and 37 carried respectively by the shafts 33 and 38. Inasmuch as the gear 39 meshes with the gear 40 on the axle 11 the middle 120 traction wheel will be rotated to move the frame in the direction in which the plows 14 point. During this operation the shaft 41 is rotated owing to the gear 42 carried thereby meshing with the gear 36 upon the shaft 33 and likewise rotary motion is imparted from the shaft 41 to the shaft 45, when the clutch members 46 and 47 are in

engagement with each other, by the gears 43 and 44 carried respectively by the shafts 41 and 45. The rotation of the shaft 45 carrying the sprockets 55 and 56 about 5 which are loosely trained the chains 57 and 58 causes the head traction wheels to be rotated since the chains are also trained about the gears 9 carried by the shafts 7 which in turn carry the said head traction 10 wheels and rotate them in the direction corresponding to the direction of rotation of the wheel 10. When the plow reaches one end of the field the hand actuating lever 54 is moved to withdraw the clutch member 48 from engagement with the member 46 to 15 prevent rotary motion being transmitted to the head wheels. During this operation the plows 14 are raised and the plows 15 are lowered. Simultaneously with this operation 20 the controlling levers are adjusted to reverse the rotation of the wheel 10. The hand wheels 64 are now rotated to shift the plow frame and after the frame and the plows carried thereby are properly arranged 25 in the ground, the clutch members are arranged in engagement with each other so that a reverse rotation will be imparted to the head traction wheels corresponding to the direction of rotation of the wheel 10. 30 When the plow reaches the other end of the field this operation is repeated to permit of the plow to travel in a reverse direction.

It will be understood that the above description and accompanying drawings comprehend only the general and preferred embodiment of my invention and that various minor changes in detail of construction, proportion and arrangement of the parts may be made within the scope of the appended 35 claims and without sacrificing any of the advantages of my invention.

Having thus fully described my invention,

what I claim as new and desire to secure by Letters-Patent, is:—

1. A motor plow including a frame, head 45 wheels connected at the respective ends of one side of the frame, another wheel rotatably mounted on the other side of the frame approximately intermediate the ends thereof, plowing means mounted at the respective ends of the frame, means for adjusting the plowing means, propelling means, means for operably connecting the propelling means with the intermediate wheel, means for shifting the head wheels, means 50 operably connected to the propelling means for rotating the head wheels, means for reversing the movement of the wheels, and clutch means for disconnecting the head wheels from the propelling means while 55 they are being shifted.

2. A motor plow including a frame composed of side bars one of which is longer than the other and cross bars connecting the side bars, arches rotatably mounted on the 65 projecting ends of the long side bar, axles journaled in the outer ends of the arches, head wheels carried by the axles, another axle journaled intermediate the ends of the other side bar, a traction wheel carried by 70 the last mentioned axle, plowing means adjustably mounted on the respective ends of the frame, propelling means, means for operably connecting the propelling means with the intermediate axle, means for operably 75 connecting the propelling means with the axles in the arches, means for shifting the direction of the head wheels, and clutch means for disconnecting the head wheels 80 from the propelling means while the head wheels are being shifted.

In testimony whereof I affix my signature.

JAMES E. WILLIAMSON.
